BENJAMIN GREENFIELD, OF NEW YORK, N. Y., ASSIGNOR TO DOHERTY RESEARCH COMPANY, OF NEW YORK, N. Y., A CORPORATION OF DELAWARE

FLUID-FUEL-FIRED BOILER

Continuation of application Serial No. 365,366, filed March 12, 1920. This application filed August 5, 1926. Serial No. 127,351.

This invention relates to fluid fuel fired boilers, and more particularly to a device for automatically controlling the supply of fuel and air to oil and gas fired boilers. The present invention was originally described in my application, Ser. No. 365,366, filed March 12, 1920, of which this is a continuation.

With the rapid development of fluid fuels (oils and gases for instance) for industrial purposes, the combustion efficiencies obtained in burning these fuels have been extremely low. This has been due mainly to the fact that fluid fuels have been used in furnaces which are not properly constructed for such combustion. The fuel losses are caused principally by overventilation, but losses may also occur from underventilation. The underventilation loss is caused by an insufficient supply of air for the fuel so that the unburned products pass out of the stack with the flue gases. The common and largest loss is caused by overventilation in which an excessive amount of air is used to burn the fluid fuel, thereby giving a decreased flame temperature and causing a very large amount of heat to be carried out of the stack with the flue gases.

To obtain the highest efficiency in the combustion of oil and gas, it is necessary to supply the fluid fuel and air for supporting combustion in such proportions that the air will just suffice to completely burn the fuel and will not be in sufficient excess of this amount to materially cool the flame or dilute the hot products of combustion. Because of the small volume of fluid fuel used, the proper proportioning of the fuel and air requires great accuracy in their control and measurement, since a comparatively large variation from the proper proportions of fuel and air is caused by a comparatively small excess or deficiency in the volume of fuel above or below that required for perfect combustion.

This accuracy of control of the volume of oil supplied can not be obtained by varying the opening of the control valves commonly used on the oil supply pipe, since the flow through these valves does not follow any definite law. This is more especially the case when the volume of oil is constantly or

frequently varied with changes in the consumption of steam from the boiler. Under these conditions the flow of oil through valves of this type can not be readily and accurately measured, nor can the measurement be accurately transmitted to an air supply controlling device. It has, therefore, been customary to supply air in a substantially constant volume and in excess of that required for perfect combustion in order to insure complete combustion during the largest fuel supply. Consequently, a large part of the heat of combustion is wasted in heating this excess of air rather than used in generating steam or for other useful work.

The primary object of the present invention is to provide a method of controlling combustion of fluid fuel by which the proper amount of air to support complete combustion is supplied to the furnace at all rates of supply of fuel.

Another object of the invention is to provide an apparatus by which the air supplied to oil and gas fired furnaces will be just sufficient to complete combustion at all rates of supply of fuel.

The rate of combustion in gas and oil fired boiler furnaces may be widely varied substantially instantaneously and may be forced at times past the limits at which good combustion efficiencies may be obtained. In addition to disturbing the conditions governing combustion, sudden variations in the rate of combustion with consequent sudden over-heating and cooling of the furnace have an injurious effect on the boiler settings, due to rapid expansion and contraction. This is more especially the case when a battery of several boilers is used to supply a variable demand for steam and when the load may be unevenly distributed so that the variation in load, and consequently in the rate of combustion, falls principally on one or on only a part of the boilers of the battery.

Accordingly, a further object of the invention is to provide an apparatus for controlling the combustion in oil and gas fired boiler furnaces in which sharp changes in the rate of combustion with changes in the load will be avoided and in which the change in the rate

of combustion in all of the furnaces of a battery of boilers will be substantially equal.

A further object of the invention is to provide an apparatus for governing the rate of supply of oil or gas to boiler furnaces in which the rate of supply of fuel will correspond to the steam consumption at all boiler loads.

In many localities, especially where natural gas is obtainable, it is customary to use both 10 gas and oil as their market prices vary, the cheapest one being used as fuel. In some cases, gas is used where available because of its cheapness and convenience, and oil is used when the supply of gas fails, the furnaces being arranged to burn either oil or gas. The 15 change from one fuel to the other makes the control or regulation of combustion much more difficult than in the case where either oil or gas alone is used because of the difference 20 in heating value and in the quantity of air required for complete combustion of equal volumes of the two fuels.

A further object of the invention is, therefore, to provide an apparatus capable of automatically controlling the combustion of both 25 gas and oil in a furnace.

With these and other objects in view, the invention consists in the method and apparatus described in the following specification and 30 defined in the claims.

The various features of the invention are illustrated in the accompanying drawing which 35 illustrates diagrammatically a plurality of steam boiler furnaces having applied thereto a fluid fuel regulating apparatus embodying the preferred form of the invention.

In the present invention, the rate of supply of fuel and air is controlled by the rate of consumption of steam from the boiler. To 40 this end, the pressure of the steam in the boiler is permitted to vary between certain definite narrow limits and corresponds to any given pressure to a definite consumption of steam. Thus, the limits may be fixed at 200 45 pounds pressure when no steam is being used, and at 190 pounds for full load, the pressures intermediate these limits corresponding to fractions of full load steam consumption. The controlling device for the air and gas or 50 oil is arranged to supply fuel and air in amounts sufficient to generate steam equal to the load demand. Thus, when the steam consumption equals 60% of a full load, the steam pressure will be, say, 194 pounds and the fuel supply will be 60% of that required for full 55 load conditions. If the load increases to 100%, the steam pressure will drop to 190 pounds and the fuel supply will increase with the drop in steam pressure until the full load 60 conditions are obtained. If the demand for steam ceases the steam pressure in the boiler will gradually build up and the fuel supply will continuously decrease until a pressure of 65 200 pounds is produced, at which point the fuel supply is at a minimum. It is not es-

sential that the change in load should be exactly proportional to the change in boiler pressure but there should be a definite load and definite fuel supply for every steam pressure between the fixed limits. The admission of fuel and air to the furnace corresponds at all times to the steam pressure of the boiler and as the pressure changes in the boiler are gradual, sharp changes in the fuel supply are avoided whether the fuel used be oil or gas.

To carry out this fuel control when gas is being used, the gas supply pipe is provided with a regulating valve which is always under the control of the steam pressure in the boiler. As the consumption of steam decreases, the 70 pressure in the boiler builds up and moves the valve towards closed position, thereby decreasing the supply of fuel to correspond to the decreased load. When the consumption of steam increases the boiler pressure falls 80 since the fuel supply is not sufficient to generate the increased amount of steam. The gas supply valve is thereby opened and the fuel supply increased to correspond to the decreased steam pressure.

When oil is being used as a fuel, the supply of oil is similarly controlled by the steam pressure of the boiler. Inasmuch as the volume of oil is much smaller than the volume of gas required for a given load, and because of the difficulty or impossibility of determining the flow of oil through control valves with sufficient accuracy, the oil is caused to pass through a standard orifice under a definite drop in pressure. The rate of flow of the oil is controlled by controlling the pressure or difference in pressures under which it is forced through the orifice. The pressure on the oil is very accurately controlled by the continuous admission to and escape from the oil of a regulated amount of gas under pressure. For this purpose, gas from the gas supply main is conducted through a steam controlled valve to an oil feeding device provided with an oil out-let orifice through which oil is fed to the boiler. A small amount of gas is always allowed to escape from the oil feeding system through an escape outlet so that the gas pressure in the oil feeding device is at all times dependent on the rate of admission of gas from the gas supply main. As the steam pressure in the boiler rises and closes the valve, the pressure on the oil supply system is decreased through a gradual escape of gas through the escape outlet and as the boiler pressure decreases, gas is admitted through the control valve faster than it can escape through the escape opening until the pressure builds up and the rate of oil supplied through the standard orifice increases proportionately.

The volumes of oil and of gas supplied under a given pressure are different but are so proportioned that the same quantity of air will be required for complete combustion of 120

the gas and oil supplied under any given pressure. A common damper control, governed by the pressure at which gas is supplied to the furnace, or the pressure at which the oil is forced through the standard orifice 5 when oil is being burned, is used for controlling the draft of air to the furnace. Since the flow of oil or gas does not vary directly as the pressure differential through the flow controlling orifice but varies as the square root of this pressure differential, in accordance with the well-known law of the flow of fluid through an orifice, the damper controlling device is so arranged that the area of the 10 damper opening will increase approximately in direct proportion to the pressure differential controlling flow of oil or gas. Furthermore, the flow of the products of combustion through the stack damper opening 15 will naturally vary as the area of the opening, and therefore by the above arrangement the rate of the feeding of the air to the furnace will vary approximately as the rate of the feeding of the fuel to the burner. Through 20 this arrangement, the firing of the furnace may be quickly changed from oil to gas or vice versa, and the proper quantity of air will be supplied in both cases without requiring any adjustment in the damper-controlling apparatus.

Referring to the accompanying drawing, gas is supplied to a furnace 10 from a gas supply main 12. The gas from the main 12 is brought to a constant low pressure by a constant pressure regulator 14 and any accidental increase in pressure after passing the regulator 14 is prevented by a pressure safety device 16. From the pressure regulator the gas flows through a gas meter 20 and through 25 a controlling valve 22 to burners 24 in the boiler furnace 10. The passage of gas through the controlling valve 22 is controlled directly by the steam pressure in the boiler 10 so that at any given boiler steam pressure 30 a definite amount of gas flows through the valve.

For this purpose the position of the valve 22 is governed by a diaphragm 26, one side of which is in communication with the steam dome of the boiler through a connecting pipe 28. As the steam pressure in the boiler increases it tends to depress the diaphragm 26 to close the valve 22. The closing action of the steam is opposed by a weighted lever 30 which tends to keep the valve 22 in an open position. The lever 30 is adjusted so that at all steam pressures below a definite minimum, say 190 pounds, the valve 22 is held in full open position. As the pressure increases 35 above 190 pounds, the valve is forced downwardly towards a closed position by the pressure transmitted to the diaphragm 26 but is prevented from moving to fully closed position at pressures slightly above 190 pounds 40 by a spring 32 which is attached to the lever

30 and which is put under tension as the weighted lever 30 rises. The tension of the spring 32 is so proportioned that as the pressure increases gradually from the minimum, 190 pounds, to the maximum, say 200 pounds, 45 the valve 22 will be gradually closed and will have a definite opening at every pressure between these limits.

The rate of supply of air for supporting combustion in the furnace 10 is controlled by 50 a damper 34 in a stack or flue 36 of the furnace in such a manner that the opening for the passage of exhaust products of combustion will be approximately proportional to the rate of flow of gas or oil. To this end the damper 34 is rigidly mounted on a rotatable shaft 38 the position of which is so governed by the pressure of the fuel gas passing to the burners 24 that the rate of flow of gases past the damper is approximately proportional to 55 the square root of the fuel gas pressure. The pressure of the gas passing from the valve 22 to the burners 24 is transmitted through branch pipes 40 and 42 to a vertically movable gas bell 44. The gas bell 44 is positioned within a tank 46 which is partly filled with water or other liquid to seal its lower end. The weight of the bell 44 is supported partly by the pressure of the gas within the bell and partly by a cable 48 which passes over a pulley 50 rigidly mounted on the damper shaft 38 and is provided at its other end with a weight 52.

As the pressure transmitted through the pipes 40 and 42 to the bell 44 increases, the bell rises and rotates the pulley 50 and shaft 38. The rotation of the shaft 38 by the rising of the bell 44 is assisted by a weight 54 adjustably mounted on a crank arm 56 formed on the shaft 38. As the bell 44 rises due to an increase in the pressure and corresponding increase in the rate of flow of flow of the gas entering the burners 24, and the shaft 38 is rotated to lower the weight 52, the moment arm of the weight 54 on the shaft 38 decreases and is proportional to the sine of the angle made by the crank arm 56 with the vertical. Since the pressure in the bell 44 must be inversely proportional to the moment arm of the weight 54 in order to have an equilibrium of forces, the damper 34 continues to open as the pressure in the bell increases until the damper comes to full open position. It has been found that with this arrangement the quantity of gases passing through the stack 36 and accordingly the air admitted to the furnace vary approximately as the square root of the gas pressure transmitted to the bell 44 and is therefore proportional to the rate of supply of oil or gas to the furnace. The pressures which may be used in the bell 44 to move the damper from closed to fully open position may be varied by adjusting the position of the weight 54 on the arm 56 or by varying the weights 52 and 54.

When oil is being used as a fuel, the admis-

sion of gas to the burners 24 and to the bell 44 is prevented by closing valves 58 and 60 in the pipes 12 and 40 respectively. A supply of oil is then forced from a feed tank 62 through a connecting U-tube 64 to an overflow tank 66. A standard orifice 68 is positioned at the end of the tube 64 which is located in the overflow tank 66. From the tank 66 the oil flows into an oil feed pipe 70 leading to 10 an oil burner 72, preferably of the steam injection type, in the boiler furnace 10.

The rate at which oil is fed from the oil feed tank 62 to the overflow tank 66 is indirectly controlled by the steam pressure in the 15 boiler 10. To this end, a small amount of gas is taken from the gas supply main 18 through a branch pipe 74 and passes through a steam controlled valve 76 to a pipe 78 leading to the top of the oil feed tank 62. The 20 pipe 78 is provided with an escape outlet 80 through which a small amount of gas may continually escape. Since all of the gas passing through the valve 76 must escape through the outlet 80, the pressure in the pipe 78 is dependent upon the rate of admission of gas 25 through the valve 76, as the rate of escape of gas through the outlet 80 is a function of the pressure in the pipe 78. The opening of the valve 76 is controlled by a diaphragm 82 which communicates with the steam chamber 30 of the boiler 10 through a branch pipe 84. As the pressure in the boiler increases, it tends to force the diaphragm 82 downwardly and close the valve 76. The downward force exerted by the diaphragm 82 is opposed by a 35 weighted lever 86 which tends to open the valve 76. The weight on the lever 86 is so adjusted that the valve 76 will be open at all pressures below a certain minimum, say 190 40 pounds, and as the pressure increases slightly above 190 pounds, it will overcome the weight of the lever 86 and move the valve 76 towards closed position. The valve 76 is prevented from moving to a fully closed position at pressures slightly above 190 pounds by a spring 88 45 attached to the weighted lever 86 and arranged to exert an increasing force as the lever is raised. The tension of the spring 88 is so adjusted that the valve 76 will not be 50 fully closed until the boiler pressure reaches a definite maximum, say 200 pounds. At all pressures between these limits, the valve will be opened a distance corresponding to the steam pressure of the boiler and accordingly 55 the gas pressure which is built up in the pipe 78 and tank 62 will have a definite relation to the steam pressure in the boiler.

Means mechanically the equivalent of the 60 spring 88 may be employed for giving a partial opening of the valve at pressures between the maximum and minimum limits. The gas pressure in the pipe 78 may be measured by a manometer 90 and recorded by a 65 recording device 92. The record of the gas

pressure by the recorder 92 will give an indication of the quantity of oil burned.

In order that the flow of oil through the orifice 68 may depend entirely on the gas pressure transmitted through the pipe 78, a constant level of oil is maintained in the oil-feed tank 62. For this purpose the tank 62 is divided into two compartments 94 and 70 96 by a partition 98 of the same height as the overflow pipe 70 and oil from a storage tank 100 is forced by a pump 102 into the compartment 94 and caused to flow over the partition 98 into the compartment 96. From the compartment 96 the oil returns to the tank 100 through a return pipe 104.

It will be readily appreciated that the pipe 70 constitutes in effect an oil standpipe or supply pipe from the foot of which oil flows to the burner 72, and that the head of oil in the standpipe depends on the rate of feed of oil from the constant level compartment 94 of tank 62 into tank 66 through the orifice 68, the rate of feed therefore primarily depending on the boiler steam pressure. It will be understood, therefore, that as the boiler steam pressure falls the supply of oil to the tank 66 increases, thereby increasing the head of oil in the standpipe 70 over the burner 72 and supplying a greater volume of oil to the burner.

The rate at which oil passes through the orifice 68 depends on the pressure in the tank 62. Therefore the amount of oil passing through the orifice 68 follows the well-known equation

$$Q = c.a.\sqrt{2gh},$$

in which Q is the quantity of oil passing through the orifice, c the orifice coefficient, a the orifice area, g the gravity coefficient, and h the pressure acting on the oil. Therefore the quantity of oil passing through the orifice is proportional to the square root of the pressure in the pipe 78. The pressure in the pipe 78 is, also,

used to control the position of the damper 34 when oil is used as a fuel. For this purpose, pressure from the pipe 78 is transmitted through a branch pipe 106 to the pipe 42 leading to the bell 44 and operates the bell 44 and damper 34 in substantially the same manner as the gas pressure transmitted through the pipe 40. The size of the orifice 68 is so adjusted to the gas burning system and to the damper controlling device 110 that the same quantity of air will be required for complete combustion of the oil or gas when the gaseous pressure transmitted through pipes 106 and 40 are the same. No

adjustment of the draft controlling mechanism is, therefore, required when the system is changed from oil to gas, since the laws governing the variation in flow of oil and gas with changes in pressure are similar. When the system is changed from an oil 115 120 125 130

burning system to a gas burning system, the supply of gas through the pipes 74 and 106 is closed by means of valves 108 and 110 respectively.

5 In adapting the apparatus for burning oil in the furnace, use has been made of combustible gas for controlling the feed of oil to the burners. It is not necessary to use gas for this purpose, but substantially any fluid 10 medium which is available at a uniform pressure may be used in the place of gas. For example, compressed air under uniform pressure may be introduced into the pipe 74 or steam under uniform pressure may be introduced in the pipe 74. When gas is used as a 15 controlling medium, the amount of gas passing through the escape outlet is comparatively small and this may be burned directly at the outlet. In case it is found desirable to 20 allow a comparatively large amount of gas to pass through the outlet 80, the gas passing through the outlet may be conducted to the boiler furnaces.

The supply of oil from the tank 62 may 25 be independently controlled by means of a pilot pipe 112 leading from the branch pipe 74 to the furnace 10. A valve 114 is mounted in the pipe 112, and when this valve is open all of the gas admitted through the valve 108 30 in the pipe 74 will flow through the pilot pipe and reduce the pressure in the pipe 78 to such a point that little or no oil will be forced through the orifice 68. In some cases, and especially where the installation is used 35 for heating oil stills and similar apparatus which are run at substantially atmospheric pressure and in which therefore the controlling valve 76 cannot be used, the supply of fuel may be controlled manually by the valve 40 114. When, therefore, the rate of combustion of oil in the furnace is to be decreased, the valve 114 is opened, thereby shutting off the supply of oil and simultaneously admitting a small amount of gas through the pilot 45 pipe 112. When the rate is to be increased, the valve 114 is closed, thereby cutting off the supply of gas through the pilot pipe 112 and building up the supply of oil through the orifice 68. The draft control operates, 50 however, through the branch pipe 106 in the same manner as in the case when the control valve 76 is employed. The escape outlet 80 is closed by a valve 117 when the pilot pipe 112 is being used and the pilot flame burns continuously, 55 the size of the flame depending upon the amount of gas flowing through the valve 114.

By maintaining a decreasing boiler pressure as the load increases and maintaining a 60 definite relation between boiler pressure and the load, advantage is taken of the fact that as the boiler steam pressure decreases the heat energy stored in the boiler is utilized in helping to supplying the increased demand 65 for steam. This in turn operates to make

the necessary changes in rate of combustion less violent, with a resultant increase in combustion efficiency and longer life of furnace linings.

The system also permits of properly proportioning the load between any number of units of a battery of boilers even though the boilers may be of varying capacity. Each boiler thus not only takes at all times its proper share of the load, but also takes its 70 proper share of the fluctuations in load, thereby contributing very materially to better combustion efficiencies and low boiler and furnace maintenance as compared with plants where a part of the boilers may be operated at a constant rate and a small part of the boilers in service be required not only to take care of all variations in load on the plant but also attempt to maintain a constant steam pressure on the main steam header. 75

By providing a separate orifice similar to 80 68 for each boiler furnace, proportioned in size according to rated capacity of the boiler and allowing its discharge to go into a separate compartment in chamber 66 and thence 90 to the proper boiler furnace and burner by means of an overflow pipe similar to pipe 70, it is possible to supply several boiler furnaces from a common feed tank 62 with the use of but one pressure controlling apparatus. 95 The oil is thus proportionally distributed to the different boiler furnaces and consequently the plant load is proportionally distributed among the boilers.

Such a system of regulation is illustrated 100 for a second boiler of the battery in the accompanying drawing. In this case a portion of the oil passing through the feed pipe 70 is withdrawn through a branch pipe and another orifice similar to 68 in a second compartment of 66. From the second compartment it is then conducted through an overflow pipe similar to 70 directly to pipe 118 and to the furnace of a second boiler 119, the 105 boilers 119 and 10 being connected by a common steam main 120. The draft through the furnace of boiler 119 is controlled by a damper 121 which is in turn governed by a bell 122 arranged similarly to the damper 34 and bell 44 of the boiler 10. The position of the bell 122 is controlled by means of the gas pressure admitted from the pipe 78 through a branch pipe 124. By means of this arrangement the amount of gases flowing past the damper 121 is at all times proportional 110 to the amount of oil supplied through 118 to the furnace of the second boiler. Similarly the branch pipe 126 conveys gas from the supply pipe 12 and a branch pipe 128 transmits pressure from the pipe 126 to the bell 122. 115

A pilot pipe 130 common to both boilers is provided to convey a small amount of oil from the tank 66 to the furnaces of boilers 10 and 119 to feed a pilot burner during 120 pe- 130

riods when the supply of oil or gas is completely shut off from main burners. The feed pipe 70 is also provided with a drain pipe 132 leading to the tank 100 through which the pipe 70 may be emptied when not in use. The pipe feeding the second boiler furnace is drained by similar means.

Because of the accuracy with which the flow of oil through the standard orifice may be restricted and controlled, and of the responsiveness and sensitiveness with which the pressure of the gas used to force the oil through the orifice may be transmitted and restricted, the apparatus is capable of maintaining under all boiler loads the proper rate of combustion and the conditions favoring the highest combustion efficiencies.

Having described the preferred form of the invention, what is claimed as new is:

20 1. In a fluid fuel fired boiler the combination of means for feeding fuel to the furnace of said boiler under a gas pressure controlled by the steam pressure in said boiler and means controlled by the pressure of said 25 gas for controlling the draft damper of said boiler furnace.

2. In a fluid fuel fired furnace the combination of means for supplying fuel oil to the furnace, a flow restricting device in said oil 30 supply means, means for supplying gas under pressure to force oil through said device, a draft controlling damper for said furnace, and means governed by the pressure of said gas for controlling the position of said 35 damper.

3. In combination with a battery of boilers having their steam spaces connected, of an oil supply chamber provided with outlets to the furnaces of said battery having 40 orifices, means for supplying fluid under pressure to said oil supply chamber, means governed by the steam pressure in said boilers for controlling the pressure of fluid in said chamber, and means for distributing 45 the oil passing through said orifices proportionally among said boiler furnaces.

4. A combustion regulator for fluid fuel fired boilers comprising an oil feed chamber, means governed by the steam pressure for 50 continuously supplying gas under pressure to such chamber, an outlet for the gas supplying means arranged to continuously permit gas to escape to control the pressure in the chamber, and an outlet for oil from said 55 chamber having a flow controlling device.

5. A combustion regulator for fluid fuel fired boilers comprising an oil feed chamber, means governed by the steam pressure of said boiler for placing said chamber under gas pressure, an escape outlet for said gas, an oil outlet from said chamber having an orifice, a damper for the furnace of said boiler having an adjustable weight rigidly mounted on its shaft at a distance from its 60 axis, a pulley on said damper shaft, and a 65

gas bell communicating with the gas space of said oil feed chamber, and arranged to rotate said pulley.

6. A combustion regulator for fluid fuel fired boilers comprising an oil feed chamber, means governed by the steam pressure of said boiler for placing said chamber under gas pressure, an escape outlet for said gas, an oil outlet from said chamber having a regulating orifice, a damper for the furnace of said boiler, and means for opening said damper a distance substantially proportional to the flow of oil through said orifice. 70 75

7. A combustion regulator for fluid fuel fired boilers which comprises an oil feed chamber, an outlet for said chamber having a regulating orifice, an oil feed pipe leading oil delivered by said orifice to the furnace of said boiler, and means for generating different pressures in said oil feed tank for 80 every boiler steam pressure between definite limits. 85

8. A combustion regulator for fluid fuel fired boilers which comprises an oil feed chamber, an outlet for said chamber having a regulating orifice, an oil feed pipe leading oil delivered by said orifice to the furnace of said boiler, means for generating a definite pressure in said oil feed chamber for every boiler steam pressure between definite limits, and means governed by the pressure in said oil feed chamber for controlling the draft to said furnace. 90 95

9. The method of regulating combustion in fluid fuel fired furnaces which comprises 100 conducting a fluid fuel stream to the furnace through a constant area flow-restricting orifice, developing a low pressure differential across the orifice to cause fuel to flow therethrough, and at intervals reducing the pressure drop across the orifice substantially to zero and automatically restoring the pressure differential to substantially suspend and automatically resume the feed of fuel to the furnace. 105 110

10. A combustion regulator for fluid fuel fired furnaces comprising a burner and mechanism for feeding a fluid fuel stream to said burner including a member provided with a flow-restricting orifice of constant area through which the fuel is fed, means for producing a low pressure differential across the orifice to cause fuel to flow therethrough, and means operable to reduce the pressure drop across the orifice substantially to zero and to automatically restore the pressure differential so that the flow of fuel to the furnace may be substantially suspended and automatically resumed. 115 120

11. In a fluid fuel fired furnace, the combination of an oil supply container, an orifice through which oil is fed from said container to the furnace, a supply of fuel gas, means for admitting fuel gas at a limited rate to said oil container, means for per- 125 130

mitting the escape of fuel gas from said container at a limited rate, and a valve controlled pilot pipe connecting the gas space of said oil container to said furnace.

5 12. In a fluid fuel fired boiler, the combination of a gas supply pipe, means controlled by steam pressure for governing the rate of supply of gas to the furnace of said boiler, a damper controlling the draft of said furnace and having a weight rigidly mounted on its shaft at a distance from its axis, a pulley on said damper shaft, a weighted cable running over said pulley, a bell attached to said cable and having a liquid seal at its lower end, and means for transmitting the pressure of the gas passing to said furnace to said bell.

20 13. In a fluid fuel fired boiler, the combination of a closed chamber for oil, an outlet for the oil in said chamber having a flow controlling orifice, means for admitting gas under pressure to said closed container, means governed by the steam pressure in the boiler for controlling the pressure of gas in said oil container, a damper for the furnace of said boiler having a weight rigidly mounted on its shaft, a weighted cable passing over said pulley, a bell attached to said cable and having a liquid seal at its lower end, and means for subjecting the interior of the bell to the same pressure as that in said oil container.

25 14. In a fluid fuel fired boiler, a closed container for oil, an outlet for oil from said container having a flow controlling orifice, means for placing said container under gas pressure, means governed by the steam pressure in said boiler for controlling the pressure of gas in said oil container, a damper 0 for the furnace of said boiler, and means controlled by the same pressure as that in said oil container for governing the opening of said damper.

30 15. In a fluid fuel fired furnace, the combination of a closed container for oil, an outlet for oil from said container having a flow controlling orifice, means for placing said container under gas pressure, a damper for the furnace, and means governed by the same pressure as the pressure of gas in said oil container for controlling the opening of said damper.

35 16. The combination with a fluid fuel fired furnace of a closed container for oil, means for maintaining a constant level of oil in said container, an outlet for oil from said container having a flow controlling orifice, means for placing said container under gas pressure, a damper for the furnace, and means governed by the same pressure as the pressure of gas in said oil container for controlling the opening of said damper.

40 17. In a fluid fuel fired boiler furnace having separate oil and gas burners, the combination of a gas supply pipe for said furnace,

a valve in said supply pipe controlled by the steam pressure of the boiler, an oil container, an outlet from said oil container having a measuring orifice, a conduit leading from said orifice to said oil burners, a branch pipe 70 leading from said gas supply pipe to said oil container, an escape outlet from said branch pipe, a damper for said furnace having a weight rigidly mounted on its shaft at a distance from its axis, a pulley mounted 75 on said shaft, a weighted cable running over said pulley, a water sealed bell connected to said pulley, and means for selectively transmitting gas pressure from said oil container or from the inlet to said gas burners to said bell.

18. In a fluid fuel fired steam boiler the combination of a gas supply pipe, a valve in said pipe controlled by the steam pressure of said boiler, a closed oil container, an outlet 85 from said oil container having a flow-controlling orifice, a conduit for leading oil delivered by said orifice to a burner in the furnace of said boiler, a branch pipe leading from said gas supply pipe to said oil container, an escape outlet from said branch pipe, a steam controlled regulating valve in said branch pipe, a damper for said furnace, and means controlled independently of the pressure in said branch pipe by a pressure 90 derived from the pressure of gas in said gas supply pipe for controlling the position of said damper.

19. In a fluid fuel fired furnace the combination of a gas supply pipe, a closed oil container, an outlet for oil from said container having a flow controlling orifice, a conduit for leading oil delivered by said orifice to an oil burner in the furnace, a branch pipe from said gas supply pipe to said oil container, an escape outlet communicating with said oil container, a regulating valve in said branch pipe, a damper for said furnace, and means controlled independently of the pressure in said branch pipe by a pressure derived 100 from the pressure of gas in said gas supply pipe for controlling the opening of said damper.

20. In a fluid fuel fired furnace, the combination of a gas supply pipe, an oil container, an outlet for oil from said container having a flow controlling orifice, a conduit leading oil delivered by said orifice to oil burners in the furnace, a branch pipe leading from said gas supply pipe to said oil container, a throttle valve controlling the admission of gas to said branch pipe, a pilot tube from said branch pipe to said furnace, a controlling valve in said pilot tube, a damper for said furnace, and means governed independently of the pressure in said branch pipe by a pressure derived from the pressure of the gas in said gas supply pipe for controlling the opening of said damper.

21. A method of controlling combustion. 130

in oil fired boiler furnaces which comprises, conducting oil to the furnace of said boiler with a gravity feed, supplying oil to the feed through a constant area restriction by means of a low gas pressure, and controlling the pressure of the gas by the steam pressure of the boiler.

22. A method of controlling combustion in oil fired furnaces which comprises, maintaining a body of oil, developing a gas pressure on the oil body to remove oil at a definite rate therefrom, conducting the oil removed from the body to the furnace by gravity, supplying air to the furnace, and controlling the supply of air to the furnace in accordance with the gas pressure maintained on the said oil body.

23. A method of controlling combustion in oil fired boiler furnaces which comprises permitting the steam pressure in said boiler to vary with variations in the load on the said boiler, maintaining a body of oil, developing a gas pressure on the oil body to remove oil at a definite rate therefrom, conducting the oil removed from said body to the furnace by gravity, and varying the gaseous pressure on the oil body in accordance with the variations of the steam boiler pressure.

24. A method of controlling the fuel supply to a battery of boiler furnaces which comprises permitting the pressures in said boilers to vary in accordance with the load on the battery, maintaining a body of fluid fuel for supplying the furnaces of the battery, developing a gas pressure on the oil body which is inversely proportional to the steam pressure on one of the said boilers, leading oil removed from the body to the individual boiler furnaces, and proportioning the oil supply between the individual furnaces of the battery.

25. A method of controlling combustion in a battery of boiler furnaces which comprises permitting the pressures in said boilers to vary with the load, controlling the supply of fuel to said battery indirectly by the steam pressure of one boiler, proportioning the oil supply between individual boiler furnaces of the battery, and transmitting the pressure under which oil is supplied, by means of a gaseous medium, to draft controlling dampers on said boiler furnaces.

26. The method of controlling combustion in an oil fired boiler furnace which comprises supplying gas at a slow rate to a body of oil, causing said oil to flow to said boiler furnace at a rate governed by the pressure of said gas upon the oil, and substantially instantaneously and completely releasing the pressure on said body of oil when the steam pressure in the boiler reaches a definite maximum.

27. A method of controlling combustion in an oil fired boiler furnace which comprises supplying gas at a slow rate to a body of oil,

causing said oil to flow to said boiler furnace at a rate governed by the pressure of said gas, releasing the gas pressure on said body of oil when the steam pressure in said boiler reaches a definite maximum, regulating the gas pressure on said body of oil and supplying air to said boiler furnace at a rate proportional to the square root of the gas pressure on said body of oil.

28. A method of regulating combustion in a furnace which comprises, maintaining a body of fuel at a constant level, conducting fuel from said body to a burner in the furnace through a conduit provided with a constant area flow restriction, supplying fuel to the burner by developing a low fluid pressure on the fuel body sufficient to force the fuel through the flow restriction, and varying the flow of fuel through the restriction between zero and a desired maximum solely by control of the pressure on the fuel body.

29. A method of regulating combustion in an oil fired furnace which comprises forcing a supply of oil through a flow restricting device to a burner for the furnace under a low pressure arbitrarily developed in accordance with the character of the burner, limiting the maximum pressure which may be developed for forcing oil through said flow restricting device, and controlling the furnace draft in accordance with the pressure employed for feeding the oil.

30. A method of regulating combustion in a fluid fuel fired boiler furnace which comprises feeding a fluid fuel stream through a flow restricting orifice to a burner in said furnace, developing a fluid pressure uniformly and substantially less than boiler steam pressure for controlling the flow of fuel through the orifice, and varying the fuel feeding pressure in inversely proportional relation with variations in the pressure of steam in the boiler.

31. A method of controlling combustion in a fluid fuel fired boiler furnace which comprises, maintaining a body of oil, conducting oil from the body to a burner in the furnace, developing a low pressure on the oil body to force oil to the burner, restricting the oil flow to the burner by a constant area orifice, supplying air to the furnace, controlling the air supply by mechanism operated directly by the oil feeding pressure, and varying the oil feeding pressure in accordance with variations in the steam demand on the boiler.

32. In a fluid fuel fired boiler the combination of means for feeding fluid fuel through a flow restricting orifice to the furnace of said boiler, means for automatically proportioning the rate of flow of fuel fed to the furnace in accordance with the steam demand on the boiler, a draft controlling damper for said boiler furnace, and means for varying the area of opening said damper

- proportionately with variations in the rate of flow of fluid fuel through said orifice.
33. A combustion regulator for oil fired boiler furnaces which comprises an oil burner, a flow restricting device for delivering oil to said burner, means for developing a low pressure upon oil passing through said device, means for limiting the pressure which may be developed on the oil, and means governed by the steam boiler pressure for varying the oil feeding pressure. 5
34. A combustion regulator for oil fired furnaces which comprises an oil burner, a closed oil container, means for conducting oil from the container to the burner through a flow restricting device, means for developing a low pressure for forcing oil through said device, means for limiting the pressure which may be developed upon the oil passing through said device, a draft control damper, a motor for operating said damper, and connections between said burner feeding device and said motor whereby the pressure developed for feeding oil will operate the damper motor. 15
35. A combustion regulator for fluid fuel fired boiler furnaces which comprises means for supplying fuel to said boiler furnace under a low pressure at a rate inversely proportional to the steam boiler pressure between definite limits thereof, means for admitting air to the furnace, and means for controlling the draft through said boiler furnace to maintain a rate of air supply substantially proportional to the square root of the pressure used in feeding fuel. 20
36. A combustion regulator for fluid fuel fired furnaces comprising a burner, means for feeding fuel to the burner including a member equipped with a flow restricting orifice of constant area through which a fluid fuel stream is fed, means for producing a low pressure differential across the orifice, and means operable to reduce the pressure drop across the orifice substantially to zero and to restore the pressure differential to substantially suspend and automatically resume the flow of fuel to the burner, said feeding means being operable to maintain a flow of fuel through the orifice whenever there is a greater pressure on the supply side than on the delivery side of the orifice. 40
37. A combustion regulator for a fluid fuel fired furnace comprising a burner, and means for feeding a fluid fuel stream to said burner including a member provided with a restricted opening of constant area and substantially uniform dimensions on two major axes intersecting at right angles through which the fluid fuel stream is fed, means for delivering the fuel to the supply side of said opening, means for developing a fluid pressure differential across the opening to force fuel therethrough, and means operable to reduce the pressure drop across the opening 45
- substantially to zero and to automatically restore the pressure differential.
38. A combustion regulator for fluid fuel fired furnaces including a burner and means for feeding a fluid fuel stream to the burner including a chamber, a hollow member associated with the chamber, an orifice plate arranged to communicate on its supply side with the hollow member, a second chamber communicating with said plate on its delivery side, means for exerting pressure on the fuel in the first chamber, and means for conducting fuel under gravity head from the delivery side of the orifice to the burner. 70
39. A combustion regulator for fluid fuel fired furnaces including a burner and means for feeding a fluid fuel stream to the burner including a chamber, means for maintaining the fuel in said chamber at a predetermined level, a pipe communicating with the chamber below the level of fuel therein and extending upwardly, a second chamber enclosing the other end of the pipe and open to the atmosphere, an orifice plate arranged to communicate on its supply side with the pipe and on its other side with the second chamber, means for conducting fuel by gravity from the second chamber to the burner, and means for imposing gaseous pressure greater than atmospheric on the fuel in the first chamber to induce flow of fuel to the burner. 75
40. A method of controlling combustion in a fluid fuel fired boiler furnace which comprises permitting the steam pressure in said boiler to vary with variations in the steam demand on the boiler, feeding fuel to the furnace at a rate which varies in accordance with variations in the steam demand on the boiler, and supplying air for supporting combustion to the furnace at a rate which varies proportionately with variations in the steam demand on the boiler. 80
41. The combination with a boiler furnace having two fuel burners mounted therein, of means for feeding fuel to each of said burners, means for supplying air to the furnace for the combustion of said fuel, mechanism for accurately proportioning the air supply in accordance with the rate of flow of fuel fed to the burner, and mechanism governed by boiler steam pressure for proportioning the fuel supply in accordance with the steam demand on the boiler. 85
42. The method of operating a fluid fuel burning furnace which consists in supplying fluid fuel and air for combustion to the furnace, and regulating the combustion in accordance with the rate of flow of fluid fuel fed to the furnace. 100
43. The method of operating a fluid fuel burning furnace which consists in supplying the fluid fuel to the furnace chamber to be burned therein, supplying air to the furnace chamber for combustion, and regulating the 105

- supply of air in accordance with the rate of flow of fluid fuel fed to the furnace.
44. The method of operating a fluid fuel burning furnace which consists in supplying an element of combustion at a constant super-atmospheric pressure head, supplying air for combustion to the furnace, and regulating the combustion in accordance with the rate of supply of said element of combustion to the furnace.
- 10 45. The method of operating a fluid fuel fired boiler furnace which consists in supplying an element of combustion at a constant super-atmospheric pressure head, supplying another element of combustion to the furnace and regulating the combustion in accordance with the rates of supply of said elements of combustion to the furnace.
- 20 46. The method of operating a fluid fuel fired boiler furnace which consists in supplying an element of combustion at a constant super-atmospheric pressure, supplying another element of combustion to the furnace, and varying the rates of supply of both of said elements of combustion to the furnace in inverse proportional relation to variations in the boiler steam pressure.
- 30 47. In a fuel-oil feeding device for a boiler furnace, the combination with a burner through which fuel is supplied to the furnace, of an oil supply pipe extending upwardly from the burner, and means for increasing the head of oil in the supply pipe in proportional relation with the fall of steam pressure in the boiler.
- 35 48. In a fuel-oil feeding device for a boiler furnace, the combination with a burner through which the fuel is supplied to the furnace, of an oil standpipe extending upwardly from the burner, and means for increasing the head of oil in the standpipe in proportional relation with the fall of steam pressure in the boiler, said means including a chamber containing oil under a constant head, a conduit leading from said chamber to the standpipe, and means for exerting a boiler pressure controlled pressure on the oil in said chamber to cause the oil to flow to the standpipe.
- 40 49. A method of regulating combustion in a steam boiler furnace fired with oil supplied to burners comprising, supplying oil under gravity head to the burners from the base of a column of oil the height of which is increased in proportional relation with the fall of steam pressure in the boiler.
- 45 50. A method of regulating combustion in a steam boiler furnace fired with oil supplied to burners comprising, maintaining a body of oil at a constant level, withdrawing oil from said body at a rate which bears an inverse proportional relation to variations in the boiler steam pressure, continuously discharging the oil so withdrawn into a standpipe to maintain a head of oil therein
- above the burner which increases in proportional relation with the rate that oil is supplied thereto, and feeding oil to the burner under the head of oil in the standpipe.
- In testimony whereof I affix my signature.
